U.S. Appl. No. 29/447,858, filed Mar. 7, 2013, Murdock.

Primary Examiner — Catherine Tuttle

(74) *Attorney, Agent, or Firm* — James T. Fondriest

(57) **CLAIM**

The ornamental design for an applicator assembly, as shown and described.

DESCRIPTION

FIG. 1 is a perspective front view of an applicator assembly embodying the new design shown;

FIG. 2 is a front view of the design shown in FIG. 1;

FIG. 3 is a left side view of the design shown in FIG. 1;

FIG. 4 is a back view of the design shown in FIG. 1;

FIG. 5 is a right side view of the design shown in FIG. 1;

FIG. 6 is a bottom view of the design shown in FIG. 1; and,

FIG. 7 is a top view of the design shown in FIG. 1.

The broken lines are included for the purpose of illustrating portions of the applicator assembly that form no part of the claimed design.

1 Claim, 4 Drawing Sheets
